UNITED STATES PATENT OFFICE.

ISAAC KINSEY, OF CINCINNATI, OHIO, ASSIGNOR TO THE STANDARD ELECTRICAL WORKS, OF SAME PLACE.

BELL.

SPECIFICATION forming part of Letters Patent No. 402,165, dated April 30, 1889.

Application filed June 14, 1888. Serial No. 277,077. (No model.)

To all whom it may concern:

Be it known that I, ISAAC KINSEY, of Cincinnati, Hamilton county, Ohio, have invented new and useful Improvements in Electric 5 Alarm-Bells, of which the following is a specification, reference being had to the accompanying drawings, forming a part thereof, in which—

Figure 1 shows a convenient form of the 10 bed-plate. Fig. 2 is the same bed-plate having the necessary holes punched through it and part of edge raised at the points *a* and *a'*. Fig. 3 shows the bed-plate formed up. Fig. 15 4 is a cap or covering to place over the electro-magnet, binding-posts, helix-piece, support, and part of the hammer. Fig. 5 shows the bed-plate having an ordinary electro-magnet, a bell attached, and covering removed.

Similar letters of reference throughout the 20 several drawings denote the same parts.

My invention consists in a new, cheap, and convenient way of constructing an electric alarm-bell, the bed-plate *P* being formed from any sheet metal and having the helix-piece *h* 25 and support *h'* and the bell-post *b* formed up, and integral parts thereof, as shown in the drawings, Fig. 3, said bed-plate *P* having convenient holes punched through it (Fig. 2) for the purpose of attaching the bell and the 30 binding-posts *c* and *c'*, the latter of which are insulated from bed-plate *P* by the interposition of some suitable non-conducting material, the helix-piece *h* and support *h'* being formed up from the plate *P*, having convenient holes punched through them for the 35 purpose of attaching an ordinary magnet-coil and bell-hammer, the edge of said plate *P*, at convenient places, *a* and *a'*, being raised to allow the notches in cap *C* to fit over them 40 and thus prevent its turning on the post *p*, to which it is secured with a screw or other suitable fastening. The binding-posts *c* and *c'* are secured to the bed-plate by screws or any suitable fastening and insulated from 45 the same by means of any non-conducting material. The notches in the bottom of the

covering *C* permit the wires to pass through to the binding-posts *c* and *c'* to connect in circuit.

The advantage of my invention over the 50 ordinary electric alarm-bell is that I construct the bed-plate ready for putting on the electro-magnet, bell, and all the attachments by three operations of the machinery—first, to cut out the metal bed-plate *P* to the proper 55 form; second, to punch out the necessary holes at convenient points to cut the helix-piece *h* and support *h'*, Fig. 2; third, to form up the bell-post *b*, the helix-post *h*, and support *h'*, Fig. 3. By these operations the bed-plate is 60 so formed that the ordinary electro-magnet, with the bell and hammer, the insulated binding-posts, and the post *b* for supporting and covering *C*, can be easily placed in position 65 and attached to the bed-plate *P* by screws or other convenient attachments; and, further, my invention can be constructed much more cheaply, and is a much more convenient form for using, it being smaller, and easily attached by means of screws or other fastenings 70 through the holes in the bed-plate *P* to the place desired.

Having thus fully described my invention, what I claim as new therein, and desire to obtain by Letters Patent, is—

As an article of manufacture, a metallic 75 bell-plate formed integral with the bell-post *b* and having perforated tongues *h* *h'* struck out of the interior thereof and bent upward from said plate to form the helix and armature supports, respectively, and tongues *a* *a'*, formed in the edge of said plate and bent upward therefrom to form lugs for holding a cover, substantially as and for the purpose set forth.

The foregoing specification of my invention signed by me, this 11th day of June, A. D. 1888.

ISAAC KINSEY.
